TOY PIRATE SHIP

Bill Markham, Los Angeles, Calif., assignor to Lakeside Industries, Inc., Minneapolis, Minn., a corporation of Delaware

Filed Oct. 17, 1962, Ser. No. 72,155

Term of patent 14 years

(Cl. D34—15)

FIG. 3

FIG. 1 is a right perspective side view of a toy pirate ship embodying my new design;

FIG. 2 is a left side perspective view thereof;

FIG. 3 is a rear elevational view thereof, the bottom being substantially plain.

I claim:

The ornamental design for a toy pirate ship, as shown and described.
